GUMMED TAPE SERVING MECHANISM

Robert A. Havemann and Donald S. Bruce, Troy,
Ohio, assignors to The Gummed Products
Company, Troy, Ohio, a corporation of Ohio

Application March 17, 1950, Serial No. 150,222

6 Claims. (Cl. 154—1.7)

1

Our invention relates to tape serving mechanism of the general type shown in the application of Robert A. Havemann et al., Serial No. 134,454 filed December 22, 1949, now Patent No. 2,614,523, and to improvements in such mechanism wherein and whereby a tear string, instead of being previously combined with a web or supply of tape to be dispensed, is separately fed from a supply and is combined with the tape during the interval of dispensing.

In such mechanism it is our object to feed a predetermined supply of gummed tape forwardly and to feed a predetermined supply of string into contact with the tape, and thereafter sever the combined tape and string into predetermined lengths. A further object of our invention is to provide means operable in conjunction with the tape and tear string feeding and cut-off mechanism to cut tear string tabs in the tape which will facilitate tearing out the string to release the seal of the tape to the container.

Basically it is our object to adopt the mechanism shown in the aforescored application Serial No. 134,454 to permit use of ordinary gummed tape in a serving mechanism and to combine the tear string with the tape coincidently with the tape dispensing operation and thereafter jointly severing the tape and string.

The foregoing objects and other objects to which reference will be made in the ensuing disclosure, we accomplish by that combination and arrangement of parts of which we have shown a preferred embodiment.

In the drawings:

Figure 1 is a side elevation with some of the internal parts indicated in dotted lines, the machine being in normal inoperative position, and with the exception of the tear string feeding mechanism and cut-off, modifications being quite similar to Figure 1 of application Serial No. 135,454 to which we have referred.

Figure 2 is a front end elevation of the machine shown in Figure 1.

Figure 3 is a slightly enlarged fragmentary sectional elevation showing the operating parts of our improved mechanism.

Figure 4 is a perspective view of the brush moistening device as modified.

Figure 5 is a perspective view of the string moistening guide added to the tape serving mechanism shown in the earlier filed application, Serial No. 134,454.

Figure 6 is a plan view of a combined tape and tear string with one type of tear string tear tab indicated.

2

Figure 7 is an enlarged fragmentary view of the upper guide plate showing the slots therein.

We will first describe the tape serving mechanism as illustrated in the previously filed application Serial No. 134,454.

Mounted upon suitable legs 1 we have shown the upright rigid side panels 2 between which the various rollers and rods forming part of the tape dispensing mechanism are journaled or supported. 10 The supply roll 3 of tape is mounted on the rollers 5 and 6. Other mechanical equivalents may be provided to support the roll or supply of tape. The tape is fed forwardly by frictional contact with a lower feed roll 7 and upper feed roll 8. 15 The feed roll actuating lever 9 is journaled as indicated at 10 on a shaft rotatively mounted between the side panels 2. The lever has a round hole 11 on its short arm which engages a pin 12 on the ratchet wheel 13. An elongated arm 28 is fixed to the ratchet wheel 13 and positioned so that its flanged end 28a will be contacted by the actuating lever 9 and moved therewith. The ratchet wheel 13 is thus driven in a clockwise direction by the actuating lever 9 which contacts both the pin 12 and the flange 28a of the arm 28. 20 A larger gear wheel 14 is also journaled on the shaft 10 and it carries the pawl 15, spring pressed as indicated at 16 to engage the ratchet wheel 13 with clockwise movement of the ratchet wheel thereby carrying around the gear wheel 14. 25

The gear wheel 14 has a set of smaller driven gear wheels 17, 18, the gear 18 being fixed on the shaft 19 which carries the lower feed roller 7. The gear wheel 18 rotates clockwise with each tape feeding operation.

30 The upper feed roll 8 is mounted in slots 20 which permit the feed roll 8 to rotate by frictional contact with the lower feed roller 7 either with tape between the rollers or with the feed rollers merely engaging frictionally. The throw of the lever 9 is controlled by an adjustable stop mechanism generally indicated at 22.

The lever 9 has an actuating handle 21 which the operator of the machine uses to advance a 40 predetermined length of tape to the brush moistening mechanism. Adjusting the mechanism 22 induces a greater or lesser throw of the feed roller 7.

A spring 24 urges the lever 9 in a counter-clockwise direction. As the tape is fed forwardly from between the upper and lower feed rollers it passes between upper and lower guide plates 25, 26. The upper guide plate 25 has a cutting edge 27 which, as will be described, functions with the 50 cut-off knife to shear off the tape crosswise of its

length after a predetermined length of the tape has been fed forwardly.

The mechanism for cutting off a predetermined length of tape and with which one of the important elements of our combination functions, comprises a dog 29 pivoted to one end of the crank arm 30 which in turn is fixed to one end of the long crank arm 32 pivoted on Journal 33. At the other end of the crank arm 32 the link 34 connects the crank arm 32 to the cut-off knife 36 pivoted at 37 (Figure 2). A spring 35 normally biases the lever arm 32 to the position illustrated in Figure 1. A roller 31 is mounted on the actuating lever 9 and with each clockwise movement of the lever 9, the roller 31 moves from its position beneath the dog 29, the dog 29 being pushed upwardly to permit passage of the roller. When the actuating lever 9 reaches the end of its clockwise movement and is released, it returns to its starting position under the influence of the spring 24. This movement of the lever arm causes the roller 31 to strike the dog 29, thereby causing a counterclockwise movement of the lever arm 32 through the intermediary of the lever arm 30 and against the tension of the spring 35. When the crank arm 32 is rocked in this manner, the end of the cut-off knife is elevated with a quick shearing stroke which cuts off the tape.

To the shearing knife 36 there is added the parts which make snipping a tear string pull tab on the leading end of the uncut tape supply possible. A cutting die, as shown in Figure 3 and consisting of the knife edged portions 38, is mounted on a base 39 which is secured with screws 40 to the knife 36. The upper guide plate 25 has a pair of slots 41, as shown in Figure 7, which permit the portions 38 to pass through the tape making lengthwise slits in the leading edge of the tape supply on both sides of the line where the tear string is secured to the adhesive surface of the tape, during the dispensing or serving operation.

The slits may be parallel with the length of the tape or they may be rounded to provide a larger tab.

It will be observed that the moistening brushes 44, as shown in Figure 4, are divided so that no moisture will be applied to a band of the tape extending on both sides of the tear string. This is to prevent the tear string and the tear tab being adhesively secured to the container.

The improved mechanism by which we independently feed and combine the tear string with the tape will now be described. This represents the invention forming the subject matter of this application as an improvement over the combination illustrated in our previously filed application Serial No. 134,454, filed December 22, 1949.

The tear string 50 is mounted on a suitable spool 51 supported on a bracket 52. The string travels in the direction indicated by the arrows in Figures 1 and 3. The string passes through the string moistening guide indicated generally at 53a which consists in an M-shaped member having legs 53, 54 secured to the brush moistening pan. The leg 53 has a slot 55 and the leg 54 has a slot 56 for guiding the tear string which forms a loop 57 underneath the cross member 58, which extends across from the legs 53, 54, well below the surface of the liquid in the brush pan. If desired, the cross member 58 may have holes through which the string may be threaded.

Passing from the moistening pan the string passes under a roller 59 and then into an annular groove 60 in the lower feed roll 7 (Figure 3).

The string then passes in the groove 60 up into position to be frictionally received between the rollers 7 and 8. Since the juncture of the string with the tape occurs at a time when the string is moist, it will adhere to the tape along its median line. Further, since the cutting off operation occurs some distance from the point of juncture of the string and tape, once the string is threaded around the moistening member 53a and under the roller 59 and in the groove 60 into contact with the tape, no rethreading is necessary during operation of the tape serving mechanism. As will be evident from Figures 1 and 3 of the drawings, the combined tape and string will be jointly severed into given lengths by the cut-off knife 36.

The slitting of the tape and the various modifications set forth in the application Serial No. 134,454 will occur during the operation of the device just as if the initial supply of gummed tape had the tear string already combined with it.

Modifications in the mechanism for feeding the tear string will readily occur to those skilled in the art, it being our purpose only to describe one suitable mechanism for combining the tape and tear string during the normal tape serving of the mechanism.

Having thus described our invention, what we claim as new and desire to secure by Letters Patent is:

1. In combination in a gummed tape serving machine provided with a tape feeding device, a supply device for gummed tape, friction rollers for feeding forwardly a limited supply of such tape, in a step-by-step operation, a guide plate under which said tape is fed having a severing edge extending crosswise of the direction of feed of the tape, a cut-off knife provided with means, synchronized with the tape feeding device, for actuating said knife and adapted to move into such relationship with the severing edge of the guide plate as to sever the tape crosswise of its length at the end of each feeding operation and cooperating means on said knife and severing edge for slitting an edge of the tape and forming a pull tab at the end of a step-by-step feeding operation, a supply device for string, and means for moistening and feeding a continuous length of string into contact with said gummed tape as it is fed forwardly by said friction rollers, said means comprising a moistening guide for leading the string through a moistening pan, and a guide for leading the string from the moistening pan into contact with one of said friction rollers, said last mentioned roller having an annular groove therein for receiving the string and carrying it into contact with the gummed tape, said annular groove being positioned so as to feed the string to a medial lengthwise position on the gummed tape.

2. In combination in a gum tape serving machine having friction feed rollers for feeding a supply of gummed tape to be served, means for feeding to said friction feed rollers a continuous strand of tear string material, said feeding means comprising a guide for passing the string through a moistening pan and leading it into contact with one of the friction feed rollers, said last mentioned friction feed roller having an annular groove therein constructed and arranged to feed the string to a medial lengthwise position on said gummed tape.

3. In a gum tape serving machine, means for serving predetermined cut-off lengths of tape and means for feeding a moistened tear string into contact with the tape and along a median line lengthwise of said tape prior to its being cut off,

said last mentioned means comprising a feed roller having an annular groove therein.

4. In a gum tape serving machine, means for serving predetermined cut-off lengths of tape and means for feeding a moistened tear string into contact with the tape and along a median line lengthwise of said tape prior to its being cut off, said last mentioned means comprising a feed roller having an annular groove therein and means effective during the cutting off operation for snipping tear tabs at the ends of the cut-off lengths.

5. In a gummed tape serving machine wherein frictional feed rollers are provided for serving a supply of gummed tape, and wherein a brush applicator mounted in a liquid receptacle is provided to moisten the tape fed from the friction rollers, means for associating a tear string with the tape as it is fed between the frictional roller, said means comprising a moistening guide for leading the tear string through the liquid receptacle and a guide roller for leading the string from the liquid receptacle into contact with one of the friction rollers, said last mentioned friction roller having an annular groove therein for receiving the string and carrying it into contact with the gummed tape, said annular groove being positioned so as to feed the string to a medial lengthwise position on the gummed tape.

6. In a gummed tape serving machine wherein frictional feed rollers are provided for serving a supply of gummed tape, and wherein a brush applicator mounted in a liquid receptacle is pro-

vided to moisten the tape fed from the friction rollers, means for associating a tear string with the tape as it is fed between the frictional roller, said means comprising a moistening guide for leading the tear string through the liquid receptacle and a guide roller for leading the string from the liquid receptacle into contact with one of the frictional rollers, said last mentioned friction roller having an annular groove therein for receiving the string and carrying it into contact with the gummed tape, said annular groove being positioned so as to feed the string to a medial lengthwise position on the gummed tape, said moistening guide being a generally M-shaped member the legs of which are secured to the liquid receptacle and have slots at their upper ends for guiding the string, the cross pieces connecting the legs of the moistening member being of a size to extend below the surface of the liquid in the receptacle and adapted to guide string into the liquid when looped therebeneath.
